United States Patent Office

Des. 217,390
Patented Apr. 28, 1970

217,390

METAL WORKING MACHINE

Charles A. Larsen, Union Grove, Wis., assignor to Gorton
Machine Corporation, Racine, Wis., a corporation of
Wisconsin

Filed Apr. 11, 1969, Ser. No. 16,691

Term of patent 14 years

Int. Cl. D15—05

U.S. Cl. D54—14

Fig. 4

FIG. 1 is a perspective view of a metal working machine embodying the new design, the view being taken generally from the front, left side thereof;

FIG. 2 is a right side view of the machine;

FIG. 3 is a front, elevational view of the machine;

FIG. 4 is a plan view of the machine;

FIG. 5 is a right side elevational view of the machine; and

FIG. 6 is a rear elevational view of the machine.

I claim:

The ornamental design for a metal working machine, substantially as shown.
